UNITED STATES PATENT OFFICE.

ALEXANDER CODAIR, OF PEABODY, MASSACHUSETTS.

MILK-BOTTLE HOLDER.

Application filed December 15, 1921. Serial No. 522,695.

To all whom it may concern:

Be it known that I, ALEXANDER CODAIR, citizen of the United States, residing at Peabody, in the county of Essex and State of Massachusetts, have invented certain new and useful Improvements in Milk-Bottle Holders, of which the following is a specification.

This invention relates to milk bottle holders, and is adapted to be secured to a portion of a building and adjacent to the door for the purpose of receiving the milk bottle to be delivered and collected by the milk man.

15 The purpose of the invention is to provide a simple and inexpensive form of holder, to be supported and retained against the side of the building up off the floor or ground and thereby out of the reach of dogs and cats thereby securing a clean and sanitary device.

Another object of this invention is to form this holder in a very simple way from a single strand of wire.

25 Further objects will be apparent from the following specifications, appended claim and drawings in which—

Fig. 1 is a side view of the holder shown attached to the wall.

30 Fig. 2 is a front view.

Fig. 3 is a plan view.

Referring to the drawing there is shown a strand of wire bent at 1 and then twisted at 3 to form loop 2 through which a nail or screw or other fastening means may be inserted through the loop and into the wall. The two ends of the wire are then bent perpendicular to the loop 3 and form the round bottom 4 upon which the bottom of the milk bottle rests. The two ends are then again twisted together as shown at 5 and bent nearly perpendicular to the base to form the side or rib 6.

The ends are then twisted at 7 and bent perpendicular to the rib and are spread out

to form the round support which helps to support and keep the bottle in place. The two ends are then again twisted at 9 and bent perpendicular to the support 8 and they fit snug against the wall as shown at 10. 50 The two ends are then again twisted as shown at 11 and form the loop 12 through which a nail or any other support may pass in order to attach it and hold it against the wall. The two ends are then bent parallel 55 to the base and are bent so as to form a round opening as shown in Fig. 3. which supports the neck of the bottle. The two ends 13 form the opening or passage way 15 through which the neck of bottle may pass 60 and they act like springs, i. e. the neck of the bottle is larger than the opening 15 so that the neck may be forced through by forcing the sides or ends 13 back to form a large enough opening at 15. When the bottle is 65 in place the ends then automatically close up and keep the bottle secure in its place. The ends are bent around as shown in 14.

Various modifications may be made within the scope of this invention without departing from the spirit thereof and the drawings are submitted for illustrative purposes only.

Having thus described my invention, I 75 claim

In a holder of the class described, a single strand of wire bent to form a loop, then bent at right angles to form a circular bottom, then bent to form a connecting link between the bottom and a round circular support for the center of the bottle, then bent to form another circular support, then bent to form a connecting link between this support and a support formed near the neck of the bottle, then bent to form an automatic 80 grip-like support, made from the ends of the wire to hold the bottle firmly in place.

In testimony whereof I affix my signature.

ALEXANDER CODAIR.
